Attorney

UNITED STATES PATENT OFFICE.

JOHN L. ARMSTRONG, OF CHICAGO, ILLINOIS, ASSIGNOR TO THE NATIONAL LOCK WASHER COMPANY, OF NEWARK, NEW JERSEY, A CORPORATION OF NEW JERSEY.

COMBINED SASH HOLDER AND WINDOW RELEASE.

Application filed April 6, 1925. Serial No. 21,151.

To all whom it may concern:

Be it known that I, JOHN L. ARMSTRONG, a citizen of the United States, residing at the city of Chicago, county of Cook, and 5 State of Illinois, have invented certain new and useful Improvements in Combined Sash Holders and Window Releases; and I do declare the following to be a full, clear, and exact description of the invention, such as 10 will enable others skilled in the art to which it appertains to make and use the same.

This invention relates to sash holders generally but more particularly to a window release device which is so combined with the 15 sash holder lever that the operation of the latter will effect the operation of such device.

Railroad car windows frequently stick at the bottom against the sill of the window, 20 and this renders it exceedingly difficult, if not quite impossible, to raise the window, and the object of the present invention is to provide a device which, when the sash holder is operated to withdraw the catch from the 25 side of the window casing, will be impinged against the window sill, and thereby cause the window sash to be slightly elevated above the sill. When the device has once been installed on a car window, its continual 30 operation will prevent any serious sticking of the bottom of the window sash to the sill.

In the accompanying drawings which form a part of this application

Figure 1 is an inside elevation showing an 35 ordinary sash holder equipped with the preferred form of the improvement, with the parts in normal position—

Figure 2 is a view similar to Figure 1 but showing the sash holder lever operated to 40 release the sash, and the impinging bolt member thrust downwardly—

Figure 3 is a view similar to Figure 1 but showing a modified form of the invention, and

Figure 4 is an elevation similar to Figure 3 but showing the position of parts after the sash holder lever has been operated to release the window.

Similar numerals of reference denote like 50 parts in the several figures of the drawing.

Referring particularly to Figures 1 and 2, 1 denotes the casing of the sash holder having formed therewith the usual dowels 2 to extend within the sash, 3 is an L-shaped 55 sash holder lever pivoted as usual to a post

4 extending from the casing, and 5 is the usual coil spring interposed between the inner lower end *a* of the member 3 and the casing whereby the action of the sash holder lever will be resilient. 60

There is nothing whatever that is new with respect to the construction above referred to since this is the ordinary sash holder such as is commonly used on railroad car windows. 65

Slidably housed within the bottom of the casing is a thrust member 6 which moves freely through a boss 7 projecting from the bottom of the casing to contact the sill denoted by *b*. 70

This thrust member 6 is a pin or short bolt which is vertically disposed and is capable of free movement through the boss 7 at the lower part of the casing 1, and this thrust member or pin is provided with a 75 head 8 whose upper surface is generally spherical as shown.

The lower end *a* of the L-shaped lever 3 is formed into a cam surface 9 whose radius is sufficiently great to render the 80 action of this cam surface gradual and therefore more forceful as will be herein-after more fully explained.

When the window, to which the improvement is applied, is closed, the boss 7 will rest 85 directly upon any suitable striker plate (not shown), that is located within the window sill, and the pin 6 will therefore be driven upwardly so that its head 8 will be in contact with the cam surface 9, and at the same 90 time the catch 10 carried by the outer face of the lower portion *a* of the lever will have been thrown by the force of the spring 5 into the usual locking engagement with the ordinary notches at the side of the widow 95 casing.

When the lever 3 is elevated to release the catch 10 the cam will be driven with great force against the head 8 of the plunger pin 6, and since the radius of this cam surface 100 is so great the operation of the cam will be all the more effective and forceful and the usual force that is applied to pinch the lever 3 upwardly toward the stationary lever 11, that is integral with the casing, will cause 105 the plunger pin 6 to exert a pressure against the striker in the window sill which will be sufficient to release the sash if the latter has become stuck to the window sill.

When the sash is elevated any consider- 110

able distance above the window sill, the pin 6 will, of course, drop by gravity, but when the sash is closed this pin will be driven by the striker plate in the window sill upwardly, until its lower extremity is flush with the lower extremity of the boss 7 and its head in contact with the cam surface 9.

If it be desired that the pin 6 shall not drop by gravity in the manner above described, a coil spring 12 may be placed around the pin and confined between the head and any suitable portion of the boss 7 so that the action of this spring will always tend to force the pin upwardly into contact with the cam surface, as clearly shown at Figures 3 and 4.

Attention is particularly called to the fact that there is no connection whatsoever between the operating lever 3 and the pin 6, and that when the window is closed the cam surface is in position to operate against the head of the pin whenever the lever 3 is elevated.

In the present improvement the force of the plunger pin 6 is initially and at all times exerted directly against the striker plate in the window casing.

This invention may be utilized in connec-

tion with window sashes other than those used in railroad cars, such as the sashes of street railway cars, busses, and even house windows, and therefore this invention is not limited in its application.

What is claimed is:—

1. A combined sash holder and window release, comprising a casing, a sash holder lever pivoted within said casing and terminating at its lower end in a cam member and a vertically disposed plunger pin slidably guided within the bottom of said casing and adapted to be forced against the window sill by the action of said member.

2. A combined sash holder and window release, comprising a casing having a boss extending from its lower face, an L-shaped sash holder lever pivoted within said casing and terminating at its lower end in a cam member, and a vertically disposed plunger pin slidably guided within said boss and having a spherical head adapted to be engaged by said member to force said pin against the window sill.

In testimony whereof I affix my signature hereto.

JOHN L. ARMSTRONG.
